Patented Feb. 21, 1961

189,800

PROJECTION CABINET FOR A FILM READER OR SIMILAR ARTICLE

Frank A. Zagara, Rochester, N.Y., assignor to Eastman
Kodak Company, Rochester, N.Y., a corporation of
New Jersey

Filed Jan. 29, 1960, Ser. No. 59,200

Term of patent 14 years

(Cl. D61—1)

Fig. 2

Fig. 1 is a perspective view of a projection cabinet for a film reader or similar article, showing my new design; and

Fig. 2 is a perspective view taken from the rear thereof.

The broken line showings of a representative film head in Figs. 1 and 2 is for illustrative purposes only.

I claim:

The ornamental design for a projection cabinet for a film reader as similar article, as shown.
